FLUID COMPRESSION DEVICE

Herbert C. Bowen, Detroit, Mich., assignor to
 Hydraulic Brake Company, Detroit, Mich., a
 corporation of California

Application January 23, 1935, Serial No. 3,043

1 Claim. (Cl. 60—54.6)

This invention relates to hydraulic brake systems and more particularly to a fluid compression device therefor.

An object of this invention is to provide a compression device having a conventional compression cylinder and interchangeable heads so that the cylinder may be readily converted into a compound compression cylinder.

Another object of the invention is to provide a fluid compression device including a cylinder having interchangeable heads.

Another object of the invention is to provide a compression device including a cylinder and means for converting the cylinder into a compound cylinder.

A further object of the invention is to provide a fluid compression device comprising a cylinder and a head therefor including a sleeve received by the cylinder to provide a cylinder having two chambers of different diameters.

Yet a further object of the invention is to provide a fluid compression device comprising a cylinder readily convertible to a large compression chamber and a small compression chamber.

Other objects and features of the invention will appear from the following description taken in connection with the drawing forming a part of this specification, and in which,—

Fig. 1 is a schematic illustration of a complete hydraulic brake installation including an improved fluid compression device;

Fig. 2 is a vertical sectional view of a fluid compression device embodying the invention;

Fig. 3 is a sectional view of a cylinder head;

Fig. 4 is a detail view.

Referring to the drawing for more specific details of the invention, 10 represents a fluid compression device including a reservoir 12 having a filling opening 14 closed as by a plug 16 provided with suitable vents 18. Formed at the base of the reservoir is a cylinder 20. This cylinder is open at both ends and has ports 22 and 24 providing communications between the cylinder and the reservoir. Generally one end of the cylinder 20 is closed as by a head 26 of a conventional type, such as is shown in Fig. 3. Preferably the head is threaded in the cylinder.

It has been found desirable to change the cylinder 20 into a compound cylinder, and to that end there is provided an interchangeable head 28. This head has a sleeve 30 which extends into the cylinder 20 to provide a plurality of chambers 32 and 34. The sleeve has a portion of small diameter which in conjunction with the wall of

the cylinder 20 provides an annular chamber or passage 36, and a plurality of ports 38 in this reduced portion of the sleeve provide communications between the chamber 34 and the annular chamber 36.

The head 28 has a discharge port 40 controlled as by a valve 42, and threaded in the discharge port is a coupling 44 connecting a fluid pressure switch 46, and the switch is connected in a circuit 48 including a battery 50 and a lamp 52, the circuit being suitably grounded as indicated at 54 and 56.

Connected to the coupling 44 are fluid pressure delivery pipes or conduits 58 and 60 connected respectively to corresponding pairs of fluid pressure motors 62, one pair for actuating the brakes associated with the front wheels of a vehicle and the other for actuating the brakes associated with the rear wheels of the vehicle. Each of the fluid pressure motors is connected between the separable ends of friction elements 64 and 66 for spreading these elements into drum engagement. As shown, each pair of friction elements is pivoted on a backing plate 68 associated with a rotatable drum 70 and the friction elements of each pair are connected to one another by a retractile spring 72.

When the cylinder 20 is converted into a compound cylinder by the use of the head 28, a compound compression piston is substituted for a conventional piston. The compound compression piston employed is substantially the same as that covered in my co-pending application filed September 16, 1933, Ser. No. 689,715.

As shown, a piston 74 reciprocable in the chambers 32 and 34 is held against displacement by a washer 76 supported on a retaining ring 78 fitted in a circumferential groove in the wall of the cylinder adjacent the open end thereof. The piston has a head 80 and a skirt 82 reduced in diameter to provide in conjunction with the wall of the cylinder 20 an annular chamber 84 communicating with the reservoir 12 as by way of the port 22.

A plug 86 threaded in the skirt of the piston provides, in conjunction with the skirt, a chamber 88 having a port 90 providing a communication between the chamber 88 and the chamber 84. The plug 86 has a groove for the reception of a leak-proof cup 92, and formed in the back of the plug is a recess 94 for the reception of one end of a thrust pin 96 the other end of which is suitably secured to a coupling 98 connected as by a boot 100 to the open end of the cylinder 20 so as to exclude dust and other foreign substances.

from the cylinder. The coupling 98 is connected to one end of a rod 102, the other end of which is connected to a foot pedal lever 104, and the lever is connected by a retractile spring 106 to a fixed support.

The head 80 of the piston has a plurality of ports or passages 108 providing communications between the annular chamber 84 and that portion of the chamber 32 forward of the head 80, and a leak-proof cup 110 fitted in a groove in the head with sufficient clearance to provide for longitudinal movement of the cup controls the ports 108. The head 80 has formed thereon a concentric sleeve 112 having a plurality of ports 114 providing communications between that portion of the chamber 32 forward of the head 80 and the interior of the sleeve. An annular washer 116 having notches 118 in its periphery to provide for disinterrupted flow of fluid is seated on the inner end of the sleeve 30, and a spring 120 is interposed between the washer and a shoulder on the head 80 for assisting in the return of the piston to retracted position.

The sleeve 112 carries a head 122 reciprocable in the chamber 34. This head has a plurality of ports 124 providing communications between the chamber 32 and the chamber 34, and a leak-proof cup 126 on the head for control of the ports 124 is held against displacement by a spring 128 interposed between the cup and the valve 42. This spring assists the spring 120 to return the piston to its normal or retracted position.

A piston 130 reciprocable in the sleeve 112 extends through the piston head 122 on the sleeve 112 and the leak-proof cup 126 on the piston head 122. The cup prevents passage of fluid past the piston. As shown, a portion of the piston 130 is reduced in cross section to form an annular passage 132 providing a communication between the ports 114 and the chamber 88 in the skirt of the piston 80. The piston 130 carries a valve 134 urged by a spring 136 interposed between the plug 86 and the valve to seat the valve on a cushioned seat 138 to close the communication between the chamber 88 and that portion of the chamber 32 forward of the piston head 80.

In the operation of the device when the cylinder is converted into a compound cylinder, upon depressing the foot pedal lever 104 the lever is moved through an angle, and this movement is transmitted through the thrust pin 102 to move the piston 74 in the chambers 32 and 34. During the initial movement of the piston 74, the cup 110 on the piston head 80 and the cup 126 on the piston head 122 close the ports 24 and 38, respectively, and pressure is received by the cup 110 on the piston head 80. As the piston advances on its compression stroke, the fluid in the chamber 32 is displaced through the passages 124 in the piston head 122, past the cup 126 into the chamber 34, and thence through the valve 42 controlling the port 40. This valve prevents retrograde movement of the fluid. The fluid passes through the valve 42, the port 40 and the coupling 44, and thence through delivery pipes or conduits 58 and 60 to the fluid pressure motors 62.

Movement of the fluid under pressure through the coupling 44 results in actuation of the switch 46 to close the circuit 48. This results in lighting the signal lamp 52. Simultaneously therewith, the fluid, moving under pressure through the delivery pipes or conduits 58 and 60, causes actuation of the fluid pressure motors 62 to spread

the friction elements 64 and 66 against the resistance of retractile springs 72 into engagement with the drums 70.

When the fluid in the chambers 32 and 34 is placed under a pressure which when multiplied by the area of the head of the piston 130 and the area of the valve 134 is slightly in excess of the load on the compression spring 136, the piston 130 is moved to trip the valve 134 resulting in relief of the pressure on the fluid in the chamber 32, and a portion of the fluid is returned from the chamber 32 through the passage 114, the chamber 88, the port 90, the chamber 84, and the port 22 to the reservoir.

As the valve 134 opens the pressure on the fluid is transferred without loss from the piston head 80 to the piston head 122 and to the piston 130. Pressure on the piston 130, however, has been reduced by relief of the pressure on the valve 134, —hence the piston 130 returns to its retracted position and closes the valve 134.

Continued movement of the piston 74 results in building up pressure in both of the chambers 32 and 34 sufficiently to again move the piston 130 and unseat the valve 134, and this operation is repeated until the pressure in the chamber 34 is of sufficient value to compress the spring 136 to retain the valve 134 in open position. This renders the head 80 ineffective.

Upon release of the applied force on the foot pedal lever 104, this lever is returned to its normal position by the retractile spring 106. During this movement of the foot pedal lever the piston 74 is moved to its retracted position under the influence of the return springs 120 and 128. Because of the limitation of space it has been found desirable to provide two return springs so that the load on the piston may be materially increased. This is not possible in instances where only one return spring is employed.

As the piston returns to its retracted position, fluid is returned from the fluid pressure motors 62 under pressure of the retractile springs 72 connected between the friction elements 64 and 66. Due to friction on the column of fluid in the chambers 32 and 34 and the delivery pipes or conduits 58 and 60 connecting the cylinder of the compression device to the fluid pressure motors, and to the tension of the springs 120 and 128, the piston 74 returns to its retracted position slightly in advance of the return of the fluid to the cylinder of the compression device. This causes a partial vacuum in the chambers 32 and 34 resulting in collapse of the cups 110 and 126 and admission of fluid from the reservoir to the chambers 32 and 34.

Upon complete return of the piston 74 to its retracted position, the ports 24 and 38 are uncovered, whereupon further pressure in the chambers 32 and 34 due to the return of the fluid from the fluid pressure motors 62 causes the cups to return to static condition, and any excess fluid returned to the chambers 32 and 34 from the fluid pressure motors 62 passes from the chambers 32 and 34 through the port 38, the passage 36, and the port 24 to the reservoir.

Although this invention has been described in connection with certain specific embodiments, the principles involved are susceptible of numerous other applications that will readily occur to persons skilled in the art. The invention is, therefore, to be limited only by the scope of the appended claim.

Having thus described the various features of

the invention, what I claim is new and desire to secure by Letters Patent is,—

5 A compressor for fluid-pressure apparatus comprising a cylinder of uniform bore threaded at one end and adapted for use either as a single or compound cylinder, a detachable cylinder head formed at one end with a sleeve-like part extending into said cylinder in spaced relation thereto and having a threaded portion intermediate its other end and said sleeve-like part engageable with the screw threads in said cylinder, a low-pressure piston directly engaging said cylinder, a tubular sleeve extending therefrom, a

high-pressure piston detachably secured to said tubular sleeve and located in the sleeve-like part of said cylinder head, said part having a port forward of the retracted position of the high-pressure piston, a plunger guided in said tubular sleeve and having a relief valve for the low-pressure cylinder, means for advancing said detachably connected pistons under applied pressure, and a spring compressed between the low-pressure piston and cylinder head sleeve for returning said pistons to retracted position. 5 10
